UNITED STATES PATENT OFFICE.

ARTHUR L. STEVENS, OF PHILADELPHIA, PENNSYLVANIA.

MOLDING-MACHINE.

SPECIFICATION forming part of Letters Patent No. 360,119, dated March 29, 1887.

Application filed October 16, 1886. Serial No. 216,394. (No model.)

To all whom it may concern:

Be it known that I, ARTHUR L. STEVENS, a citizen of the United States, residing at Philadelphia, in the State of Pennsylvania, have 5 invented an Improved Molding-Machine, of which the following is a specification.

My invention relates more particularly to machinery for molding car-wheels, and is fully described in the following specification and 10 illustrated in the accompanying drawings, which form a part thereof.

Figure 1 is a longitudinal section through the machine. Fig. 2 is a detail in perspective of the automatic sand weighing or measuring 15 device. Fig. 3 is a section through the sand-distributing cones. Fig. 4 is a plan of the top of the cones, while Fig. 5 is a plan of the bottom of same.

In Fig. 1, 1 is a pit for the reception of sand. 20 Running over suitable wheels in the pit 1 is the elevator belt or chain 2, provided with buckets 3. Near the top of the machine, and supported by suitable bearings, are wheels 4, and below these are the guide-wheels 5.

25 6 is a chute having one or more spouts, 7, for delivering the sand into the buckets 8. In the bottom of the spouts are openings fitted with dampers 9, which are provided with the cranks 10 and connected to the hinged 30 piece 12 by the connecting-rod 11. The buckets 8 are hung upon trunnions 13 in bearings 14 and 15. Bearing 15 is placed upon the hinged piece 12. The piece 12 is raised against the stop 16 by weights 19, suspended by the 35 cord or chain 17, running over wheels 18. From the chute 6 is a spout, 20, for discharging superfluous sand into the pit 1. Directly under the bucket 8 is the conical hopper 21. Joined to the bottom of this hopper is the neck 22, in 40 the form of a truncated cone, with its widest end or opening downward where it joins the bottom casing, 23. This bottom casing is nearly as large in diameter as the flask to be filled. Suspended in the interior of the casing 23 by supports 50 are a series of concentric 45 conical distributors, 24, 25, 26, 27, and 28. Under these cones the car 30, provided with a flask, 29, is placed. After the flask has been filled it is pushed under the cylinder or drum 50 31, where the surface is struck with a sweep, 32, carried on the lower end of the vertical shaft 33. This shaft is capable of being raised and lowered by any suitable device, and is caused to rotate by the bevel-gears 34. Gears

34 follow gear 35, driven by pulley and belt. 55 The cylinder 31 may be provided with an opening, through which any sand that may be removed by the sweep will be thrown into the pit 1. Such an opening is not shown, as it is not essential to the operation of the machine. 60

From under the drum 31 the car and flask are moved onto the rails 36 on top of the ram or plunger 37. This ram is raised or lowered by liquid-pressure in the cylinder 38. Cylinder 38 is suspended in a pit, 39, from the 65 girders 40. Upon the bottom girders, on both sides of the cylinder 38, are the posts 41. To these posts is secured the pattern 42, which is to define a part of the mold. The posts on both sides are connected at the top by girders 43. 70 Between these girders are cross-girders 44, upon which is supported the cylinder 45, having the ram or plunger 46. To the lower end of the ram 46 is secured, by means of screws 47, the pattern 48, which, in conjunction with 75 the pattern 42, defines the mold.

As every mold is composed of two parts, known as the "cope" and "drag," I prefer to build these machines with separate distributors, sweeps, and presses for each part. Fig. 80 2 shows how the buckets 8 are placed on each side of chute 6, with spout 7 over each. Distributing-cones are placed under each of these buckets, and I place two cylinders, 31, side by side for the cope and drag, and also two presses. 85 Fig. 1 shows the distributors, sweep, and press for the drag. Those for the cope would be duplicates of these, and therefore are not shown. The hopper 21, where it joins the neck 22, is much narrower than the diameter of the bucket 90 8, for the purpose of collecting the sand in a compact body or mass to be cut and distributed as evenly as possible by the cones. The neck 22 has its lower end somewhat larger than its top, to prevent clogging and to allow the sand 95 to fall freely upon the upper edges of the distributing-cones 24, 25, 26, 27, and 28. These cones have the size of their upper and lower openings so regulated as to distribute the sand over the bottom of the flask with a depth varying from the center outward, to conform approximately to the contour of the wheel to be molded. In Fig. 3 such a contour is represented by the dotted line 49.

Referring to Fig. 4, it will be seen that the 105 concentric openings between the cones 24 and 25 and between 25 and 26 are proportionately much larger than between the other cones,

while in Fig. 5 it will be seen that those spaces are much narrower than the spaces between the other cones.

It will be further noticed by reference to Fig. 3 that the varying depth of sand required in flask, as represented by the dotted line 49, is the deepest under the spaces between 24 and 25 and between 25 and 26. As these spaces receive the greatest proportionate quantity of sand from the hopper and distribute it in a less proportionate area in the flask, the sand thus distributed must vary proportionately in depth. By changing the relative area of any of the concentric spaces at the top, varying quantities of sand may be discharged through the several spaces, and by varying the diameter of the cones at the bottom these varying quantities of sand may be distributed in the flask in rings or ridges with a resulting graduated depth to approximate the depth required in the completed mold. In all cases the spaces between any two cones should expand in size from the top downward to prevent clogging or choking of the sand. Any number of cones may be used that is found necessary by the size and character of the work.

The operation of the machine is as follows: Sand, being supplied to the pit 1, is elevated to the bucket 8. When the required quantity has been obtained, the weight of the bucket exceeding that of the weight 19, the hinged piece 12 is forced down, and through the connecting-rod 11 and crank 10 raises the damper 9, as shown by dotted line in Fig. 2. The sand from the elevator-buckets now falls through the opening thus made into the chute 6, down the spout 20, back to the pit 1. A flask having been placed under the distributing-cones, a workman swings the bucket 8 upon the trunnions, dumping the sand into the hopper 21. The weight 19 now raises the hinged piece 12 against the stop 16, closing the damper 9 and allowing the sand to again fill the bucket 8. The sand dumped from the bucket into the hopper 21 is collected in a compact body in the neck 22, then falls through the distributing-cones into the flask with such varying depth as before described. From under the distributing-cones the flask is moved under the cylinder or drum 31. The rotating sweep is caused to descend, sweeping and evening the surface of the sand, producing a further and more perfect distribution, and shapes the surface to the required contour. Any superfluous sand is removed by the sweep and thrown by centrifugal force into the drum 31, from which it is removed. The flask, with the sand thus prepared by the sweep, is moved onto the press. Ram 37 is then forced upward, imprinting the sand in the flask against the pattern 42, where it remains until the ram 46 is forced down, imprinting pattern 48 against the remaining portions of the sand. The ram 37 is then allowed to fall, while the ram 46 and pattern 48 follow it, until the flask and sand descend below pattern 42, when the pattern 48 is raised. The object of this move-

ment is to remove pattern 42 from the sand while the latter is held and supported by the pattern 48.

A uniform density in the mold is obtained by the quantity of sand in the flask being apportioned according to its depth after pressing; but this, however, is not a part of my invention; but

What I do claim as my invention, and wish to secure by Letters Patent, is—

1. In a molding-machine, the combination of a measuring-bucket, a conical hopper, and a series of concentric distributing-cones, arranged substantially as shown and described. 80

2. In a machine for molding car-wheels, the combination of the measuring-bucket 8, hopper 21, with neck 22, and the distributing-cones 24, 25, 26, 27, and 28. 85

3. In a molding-machine, the combination of the bucket 8, trunnions 13, hinged piece 12, connecting-rod 11, damper 9, spout 7, stop 16, weight 19, and the hopper 21, and a series of concentric distributing-cones, substantially as 90 described.

4. In a molding-machine, the combination of a measuring-bucket, conical hopper with diverging neck and a series of concentric conical distributing-cones, and a flask. 95

5. In a molding-machine, the combination of the elevator-buckets 3, spout 7, damper 9, and the measuring-bucket 8, trunnions 13, hinged piece 12, connecting-rod 11, and weight 19, substantially as described. 100

6. In a molding-machine, the combination of a measuring-bucket, conical hopper, concentric distributing-cones, and a revolving sweep, substantially as shown and described. 105

7. In a molding-machine, the combination of the measuring-bucket 8, hopper 21, with neck 22, distributing-cones 24, 25, 26, 27, and 28, and sweep 32 and drum 31, substantially as described. 110

8. A molding-machine consisting of a measuring-bucket, conical hopper, concentric conical distributors, a revolving sweep, and a press with a flask-supporting ram adapted to move upward against a pattern and a pattern-carrying ram adapted to move downward against the sand, substantially as herein described and illustrated. 115

9. A machine for molding car-wheels, consisting of the bucket 8, hopper 21, neck 22, cones 24, 25, 26, 27, and 28, drum 31, cylinder 38, ram 37, pattern 42, cylinder 45, ram 46, and pattern 48. 120

10. A machine for molding car-wheels, consisting of the flask 29, spout 7, damper 9, spout 20, bucket 8, trunnions 13, hinged piece 12, connecting-rod 11, weights 19, hopper 21, with neck 22, distributing-cones 24, 25, 26, 27, and 28, sweep 32, drum 31, ram 37, pattern 42, ram 46, pattern 48, and adjusting-screws 47. 125
